UNITED STATES PATENT OFFICE.

OTTO SUPE, OF SAULT STE. MARIE, MICHIGAN.

DESIGN FOR A SPOON.

SPECIFICATION forming part of Design No. 21,740, dated August 2, 1892.

Application filed June 2, 1892. Serial No. 435,314. Term of patent 3½ years.

To all whom it may concern:

Be it known that I, OTTO SUPE, a citizen of the United States, residing at Sault Ste. Marie, in the county of Chippewa and State of Michigan, have invented and produced a new and original Design for Spoons, of which the following is a specification, reference being had to the accompanying drawing.

The leading feature of my design is a spoon having in the bowl the illustration of a lock and a vessel therein with a part of the lower level of the water and a portion of the bank.

My design, which is shown in the accompanying drawing, represents a view of the bowl of a spoon bearing the aforesaid illustration.

The design is shown as applied to the bowl of a spoon, the walls of the lock and the gates being located along the central portion of the bowl, with steps at the sides, and the hull and masts of a vessel showing above the gates of the lock.

The design may be applied to any form of tea, coffee, orange, or other kind of spoons.

I claim—

The design for a spoon, as herein shown and described.

OTTO SUPE.
